UNITED STATES PATENT OFFICE.

GARTH G. GILPIN, OF RIVERSIDE, ILLINOIS, ASSIGNOR TO UNION METAL PRODUCTS COMPANY, OF CHICAGO, ILLINOIS, A CORPORATION OF DELAWARE.

END WALL FOR RAILWAY CARS.

Application filed March 8, 1926. Serial No. 93,255.

Reference is had to the accompanying drawings, which illustrate the preferred form of the invention, though it is to be understood that the invention is not limited 5 to the exact details of construction shown and described, as it is obvious that various modifications thereof within the scope of the claims will occur to persons skilled in the art.

10 My invention relates to the construction of a railway car having an end wall made of one or more metallic plates secured together and reinforced with stiffening and bracing members. While efforts are made 15 to block the lading in the car, the shocks caused by the heavy locomotives, the emergency air brake and the classification hump tear the lading away from its moorings and throw it against the end of the car, and the 20 lateral weaving of the car throws it against the side of the car. The invention is readily adaptable to box, gondola and other types of railway cars.

One of the objects of the invention is to 25 provide a wall element which has great strength to resist the torsional and weaving stresses which exist in a railway car when moving in service. These stresses are caused by the inertia of the roof and 30 superstructure when the train is suddenly stopped; rough or uneven track; the superelevation of the track on curves; the lateral inertia in rounding curves; eccentric thrust due to the lading 35 being secured to one side of the car; the cars being "cornered"; the use of push pole pockets, etc. Such stresses rack and distort the superstructure which decreases the life of the car, and also causes the car to 40 leak grain, sand, and other such material. Furthermore, such stresses cause leaky roofs and leaky and inoperative side and end doors.

The tendency of present designs of all 45 metal end walls to bulge is resisted partially by the corrugations, stiffening members or whatever means have been provided to transmit such stresses to the side wall or frame members of the car. Such tendency 50 is also resisted by the corner post of the car acting as a vertical beam supported at its top and bottom and sustaining a horizontal load; in other words, the bulging of the end would pull the opposite corner posts 55 toward each other. This bulging also tends

to pull the end (or side) plate downwardly and the end (or side) sill upwardly.

In my construction the end wall is resiliently or yieldingly attached to the frame members of the car and the stiffening means 60 terminate within this resilient arrangement and are not attached to the car frame members. With such a construction the strains and distortions of a bulging end wall are not transmitted to the frame members of 65 the car. The strains of a bulging end wall are concentrated in the end wall itself and not distributed to other parts of the car, thus reducing the cost to repair the car and simplifying the replacement of the end 70 wall.

Another object of the invention is to attach an end wall to a railway car so that its distortion, due to bulging, is not transmitted to the adjacent frame members of the 75 car.

Another object is to form a depressed panel in a metallic end wall which reinforces and strengthens the end wall and at the same time provides a bearing surface for 80 lining boards.

In the drawings:

Fig. 1 shows an end elevation of a railway box car with my invention applied 85 thereon.

Fig. 2 is a section on line 2—2 of Fig. 1.

Fig. 3 is a section on line 3—3 of Fig. 1.

Fig. 4 shows a modification wherein the transverse beams are positioned horizontally.

The usual railway box car is provided with an end sill 1; end plate 2 and corner posts 3 which constitute a rectangular frame for the end wall. The bottom of the end plate 2 sometimes conforms to the slopes of 95 the roof. In a gondola car the top end chord is a frame member.

My end wall comprises one or more metallic plates 4—5 connected together and secured to the above mentioned end frame. 100 The end wall has a central portion 6 offset (preferably depressed inwardly toward the car) so as to form a continuous web 7 adjacent the end frame. This continuous web, however, is not secured to the end frame so 105 that if the end wall bulges its distortion is not transmitted to the end frame members.

The offset central portion 6 of the end wall is reinforced by a plurality of transverse beams 10—11 which cross the cen- 110

tral portion and are preferably the same depth as the continuous web 7. These beams terminate adjacent the opposite portions of the web and are not secured to the adjacent frame member so that any distortion or deflection of any of these beams is not transmitted to the end frame of the car.

In the preferred form there are a plurality of plates connected on horizontal lines forming the end wall with a central reinforcing beam 10, as shown in Fig. 1.

It is desirable to line metallic end walls with wooden boards to prevent the moisture on the inside of the metallic plate, due to condensation, from coming in contact with the lading; furthermore, such wooden lining boards act as cushions to absorb minor shocks caused by the shifting of the lading. In order to line my end wall I provide wooden nailing strips 20 positioned between the continuous web and the adjacent frame member, which nailing strip is preferably secured to the end wall either at the marginal portion, as shown in Fig. 3, or it may be secured to the continuous web. The lining boards 21 are preferably positioned normal to the direction of the reinforcing beams and are nailed or otherwise secured to the nailing blocks and are also preferably secured to the central beam by bolts 22 or other means, therefore, when the end bulges the lining boards simply bend or deflect with it. The lining boards are in contact with the offset portion of the metallic plate so that they are backed up or supported over substantially the entire area of the end wall.

In Fig. 4 the plates 30—31 are connected along horizontal lines and the transverse beams 32 are also positioned horizontally.

40 I claim:

1. In a railway car having four members constituting a substantially rectangular frame for an end wall; the combination of an end wall secured to said frame having an offset central portion forming a continuous web with portions parallel to and adjacent each of said members but not secured thereto, and a plurality of transverse beams crossing said offset portion terminating adjacent the opposite portions of the web.

50 2. In a railway car having four members

constituting a substantially rectangular frame for an end wall; the combination of an end wall secured to said frame having an offset central portion forming a continuous web with portions parallel to and adjacent each of said members but not secured thereto, and a plurality of transverse beams crossing said offset portion terminating adjacent the opposite portions of the web, which beams are substantially the same depth as the web.

3. In a railway car having four members constituting a substantially rectangular frame for an end wall; the combination of an end wall comprising a plurality of plates connected along horizontal lines secured to said frame having an offset central portion forming a continuous web with portions parallel to and adjacent each of said members but not secured thereto, and a central vertical beam crossing said offset portion terminating adjacent the opposite portions of the web.

4. In a railway car having four members constituting a substantially rectangular frame for an end wall; the combination of an end wall secured to said frame having an offset central portion forming a continuous web with portions parallel to and adjacent each of said members but not secured thereto, wooden nailing strips, a central vertical beam crossing said offset portion terminating adjacent the opposite portions of the web, and a wooden lining bearing against said offset portion and secured to said nailing strips.

5. In a railway car having four members constituting a substantially rectangular frame for an end wall; the combination of an end wall secured to said frame having an offset central portion forming a continuous web with portions parallel to and adjacent each of said members but not secured thereto, wooden nailing strips secured to said wall, a central vertical beam crossing said offset portion terminating adjacent the opposite portions of the web, and a wooden lining bearing against said offset portion and secured to said nailing strips and said vertical beam.

GARTH G. GILPIN.
